UNITED STATES PATENT OFFICE.

NILS W. NORDSTROM, OF BROOKLYN, NEW YORK.

REMOVABLE DENTURE.

1,251,912.

Specification of Letters Patent.

Patented Jan. 1, 1918.

Application filed November 18, 1916. Serial No. 132,094.

To all whom it may concern:

Be it known that I, NILS W. NORDSTROM, a citizen of Sweden, and resident of the borough of Brooklyn, in the county of Kings 5 and State of New York, have invented certain new and useful Improvements in Removable Dentures, of which the following is a specification.

This invention relates to improvements in 10 dental bridgework, and more especially appertains to an improved construction of removable dentures.

One of the objects of the invention is to produce a device of the character described 15 including a strong and properly guided support for artificial teeth which shall be capable of self adjustment into its assigned position.

Another object is the provision of a device 20 of the nature set forth embodying means for securely locking it to an adjacent receiving part without interfering with its self-adjusting features.

A further object is to provide a device of 25 the species mentioned that can be quickly applied to the receiving part and will readily find its bearing surface, from which it may be as promptly disengaged.

Other objects and advantages will become 30 apparent as the specification proceeds.

With the aforesaid objects in view the invention consists of the improvements, novel construction, arrangements and combinations of parts hereinafter described, defined 35 in the subjoined claims, and illustrated in their preferred embodiments by the annexed drawing, wherein like elements are designated by the same reference characters throughout.

40 In the said drawing, which is made on an enlarged scale in order to illustrate clearly the invention in its minutest details:—

Figure 1 is a top plan view of a lower denture with the invention applied thereto 45 in the form of a double attachment replacing four molars, that is, two on each side of the mouth, certain parts being shown in section and others in changed positions;

Fig. 2 is a fragmentary side view of the 50 rear portion of the denture appearing in the upper half of Fig. 1;

Fig. 3 is a sectional plan view representing a modified form of locking element included in the artificial denture;

Fig. 4 is a right hand side view of the 55 construction shown in the preceding figure;

Fig. 5 is a sectional side elevation of the modified structure, as shown in Fig. 3; and

Fig. 6 is a detail view of a joint in the denture, shown on an enlarged scale. 60

In these views, the reference letter A denotes a natural tooth, which is technically termed the second bicuspid and forms part of the denture on either side, as seen in Fig. 1. For purposes of the invention, this tooth 65 is capped with a crown B, which may be of gold or some other suitable material, cemented on in accordance with approved practice. The crown B serves to hold in a substantially vertical position a guide post 70 11, connected therewith by means of a rib or web 12, of less thickness, preferably at a point approximately in line with the inner faces of the molars to be replaced.

The reference numerals 15 and 16 represent 75 artificial molars, shown in the lower part of Fig. 1, which are respectively embedded in recesses 17 and 18, indicated in the upper part of the same figure and provided at the surface of a saddle 19, adapted to be 80 seated upon the alveolar ridge C, in rear of the said tooth A. The saddle 19 may extend rearwardly of the space previously occupied by the wisdom tooth, if the latter be missing, as suggested in Fig. 1 or it may 85 terminate at the wisdom tooth, if existing in the denture. The invention is of such character that it requires no support from the latter-named tooth, whether present or absent. 90

Forwardly of the said artificial molars is a pair of slide jaws 22, 23, arranged to embrace and surround the guide 11, from the side opposite to that of the rib 12. These jaws are preferably formed with a backing 95 24, attached to a box-like lining 25, which is made to cover the walls of a recess provided in the inner side of the saddle 19, for a purpose to be presently described.

The recess having the box or lining 25 is 100 open on the inner side of the alveolar ridge and is intersected in a vertical direction at its forward edge by the guide 11, previously mentioned. A lever 26, arranged to swing in a horizontal position, is placed in this recess and has a working fit in its said box or lining within which it is intermediately pivoted by means of a vertically disposed pin 105

27, located a short distance rearwardly of the said guide. An operating head 28 is provided at the rear end of the lever 26, and forwardly the lever is formed with a slightly curved nose portion 29, adapted to be swung into contact with the guide 11, in such a manner as to exert a binding or crowding pressure upon the latter when the said lever bears endwise thereon, as indicated in the 10 lower half of Fig. 1. When the lever is swung away or disengaged from the guide, its nose portion is received in an extension 30 of the box 25, as shown in the upper part of the said figure. Both ends of the lever, 15 it will be noted, are shaped so as to conform with and closely following the adjoining faces of the box or lining, and thereby prevent entrance of particles of food or matter into the same. The box or lining is 20 conveniently set or molded into the material of which the saddle is composed, the latter being made preferably of gutta-percha in the usual manner.

From the foregoing it is apparent that 25 the saddle bearing the artificial teeth engages the alveolar ridge independently of the means for connecting it to the adjacent natural tooth. It is self-adjusting over the ridge both in a vertical and in a horizontal 30 direction and the adjustment remains unaffected during mastication as the engaged parts 11 and 26 then coact in preventing the artificial portion of the denture from rising.

A short neck 31 is added to the operating 35 head 28 which is thereby offset from the lever 26 and the entrance to the recess wherein the latter is pivoted. The neck 31 provides a space sufficiently wide for the insertion of a finger nail or a tooth-pick or other 40 suitable instrument to pry the head 28 out and swing the lever on its pivot so as to force the nose portion 29 away from the guide post 11.

The forward artificial molar 15 may be 45 grooved or recessed as at 32, to afford ready access to the pivot pin 27 and permit withdrawal thereof by means of some suitable implement, to repair or renovate the same.

As shown in Figs. 3, 4 and 5, the guide 50 post 11 is cut into at 33, in order to produce thereon a lateral seating surface adapted to be engaged by the nose portion 29 of the lever 26. This prevents the attachment from being pulled off unless the head 28 is swung 55 a considerable distance away from the box 25. The attachment thus secured is especially fitted for inverted dentures, that is, such as pertain to the upper jaw.

Figs. 3 and 4 also show the head 28 formed 60 with a slot or gap 31^a, instead of being offset as before described. It is understood of course, that the slot or gap provides the space required for the reception of the prying instrument.

65 Where artificial teeth are supplied on both

sides of the jaw, as represented in Fig. 1 for example, they are preferably combined and applied conjointly so as to lend support to one another. This is accomplished easily by means of a light bar 34, of semi-circular 70 cross section, following the curve of the natural teeth on the opposite sides. The ends of the bar 34 may be brazed or welded to the bottom wall of the box 25, and also enveloped by the rubber or other material of 75 which the saddle 19 is made.

In a case, where a single artificial denture is required that is, at only one side of the mouth, the bar 34 can be of a very much shorter length, and its outer or free end 80 may be anchored to or around any one of the sound teeth, so as to prevent the saddle from working sidewise. Furthermore, the dental attachment hereinabove described can be used for other teeth than those exemplified in the accompanying drawing without sacrificing any of its principal advantages.

While certain preferred embodiments of 85 this device have been shown and described, it will be understood that changes in the form, arrangements, sizes, proportions and details thereof may be made without departing from the scope of the invention as defined by the appended claims. 95

Having described my invention what I desire to secure by Letters Patent and claim is:—

1. A dental attachment including a member applicable to the alveolar ridge in a 100 vertical direction, a guide anchored to an adjacent tooth opposite one end of said member, means on the latter for engaging said guide, and a fulcrumed binding element adapted to bear positively on the guide 105 so as to hold the member away from said tooth.

2. A dental attachment including a member capable of self-adjustment upon the alveolar ridge, a guide post adjoining one end 110 of said member, means for rigidly holding said post from an adjacent tooth, a pair of jaws at said end of the member engaging opposite sides of said post, and a binding element arranged to bear positively on the 115 latter oppositely to said jaws from the same end of the member.

3. A dental attachment including a member overlying the alveolar ridge, means for anchoring said member to an adjacent tooth, a positively actuated binding element operating to press the member oppositely to 120 said means, and a brace extending past said tooth from the anchored end of the member in a direction opposite to said binding element.

4. A dental attachment including a member adapted to overlie the alveolar ridge and having a recess above the latter, means for holding said member to an adjacent 125

- tooth, a laterally open box in said recess, and a locking lever pivotally mounted in said box in position for engagement with said anchoring means in a longitudinal direction.
- 5 5. A dental attachment including a member fitted for superimposition upon the alveolar ridge, anchoring means disposed for vertical engagement between said member and an adjacent tooth, and a locking lever
- 10 mounted to oscillate in a horizontal plane relatively to the member, one arm of said lever being adapted to exert an endwise

thrust on said anchoring means, and the other arm of the lever carrying a head whereby the same can be operated. 15

Signed at the borough of Manhattan in the county of New York and State of New York this 14th day of November, A. D. 1916.
